UNITED STATES PATENT OFFICE.

ELMER A. RICH, JR., OF WILMETTE, ILLINOIS, ASSIGNOR TO THE AMERICAN FOUNDRY EQUIPMENT COMPANY, OF NEW YORK, N. Y., A CORPORATION OF DELAWARE.

SAND CUTTING AND CONVEYING MACHINE.

Application filed September 8, 1921, Serial No. 499,182. Renewed March 18, 1927.

My invention relates to machinery for treating sand for foundries and for similar purposes.

One of the objects of the invention is to provide a machine which can cut, riddle and pile the sand.

Another object of the invention is to permit the ready and quick arrangement of the machine to perform any desired one of its 10 different functions.

Another object of the invention is to secure simplicity and compactness in construction.

Another object of the invention is to arrange for the ready and effective operation and control of the various mechanisms involved in the operation of the machine.

In the accompanying drawings Fig. 1 is a side elevation of a machine of the class 20 specified embodying my invention;

Fig. 2 is an end elevation looking toward the right hand end of the machine in Fig. 1;

Fig. 3 is a plan view of the machine.

Referring to the drawings I show a machine having front wheels 1 and rear wheels 2 and a body frame having members 3—3 connecting and supported by said wheels. Both the front and rear wheels are mounted 30 on individual axes and the front wheels are provided with forks 4—4, the axes 5 of which are connected together by means of a cross bar 6, and a handle 7 permits the adjustment or turning of the front wheels for 35 steering the machine. The rear wheels 2 are driven to propel the machine in either direction. The driving mechanism will be described later on.

The machine is provided with means for 40 cutting, mixing and piling the sand, as for example a rotary cutter 8 having transversely extending cutting blades 9. This cutting device 8 may be employed to cut the sand by rotating it to throw the sand in a relatively 45 backward direction when the machine is going from left to right (Fig. 1). It may also be used to pile the sand by throwing the sand forwardly when the machine moves from right to left (Fig. 1). This cutting 50 and piling device 8 is mounted so as to permit it to be raised and lowered so as to place it in position close to the floor or ground and also to lift it materially above the same.

As an arrangement for permitting the 55 vertical adjustment of the cutting device 8, said

device is mounted at the end of side beams 16 which run to and are pivoted on a main driving axis 17. Also flexible connectors 18 are attached to the ends of the cutting device 8 and passed over overhead pulleys 19 and 60 thence down to a reel 20 having a handle 21 by which the connectors 18 may be wound or unwound and the cutting device 8 raised and lowered, the latter swinging about its pivotal axis 17. The rotary cutting device 8 is 65 driven by a sprocket chain 23 driven from the shaft 17, the latter being driven by a pinion 24 meshing with a gear 25 on the shaft 17, the pinion 24 being on the driving shaft of the power generator, preferably an 70 electric motor 26. By turning the reel 20 by its handle 21, cutting and piling device 8 may be raised and lowered into and out of operative position, and said device may be rotated in either direction by motor 26. 75 Mechanism for riddling the sand is also provided. This may consist of a traveling conveyor 10 for elevating the sand and a vibratory support or hopper 51 arranged to receive the sand elevated by traveling conveyor 80 or elevator 10. The vibration of support or hopper 51 causes sand dumped thereon to be shaken down so that it falls upon the floor or other suitable place, whereas the rails, gangers, etc. remain on the support or hopper 51, thereby effectively riddling the sand. 85

The travelling conveyor or elevator 10 is mounted so that it can be raised and lowered to permit of its lower end being placed close to the ground and also to permit the whole device to be elevated well out of the way. Preferably arrangement is made so that the elevator 10 and cutter 8 may be alternately placed in substantially the same operative position, either one or the other being so located, according to the one it is desired to operate. The conveyor includes buckets 11 that are hinged at their upper and rear margins to the conveyor chain to permit the chain to travel around the sprocket wheels at the ends 90 of the conveyor. When the buckets are loaded, the rear sides thereof lie against the chain as the buckets rise.

As an arrangement for raising and lowering the elevator 10, I show flexible connectors 28 connected with blocks 29 on said elevator, the connectors 28 passing over pulleys 30 and 31 and thence down upon and over a reel 32 by which the connectors 28 may be wound and unwound to raise and 100 105 110

lower the conveyor. The upper end of the conveyor is pivotally connected at 34 with swinging arms 35 pivoted at 36 by which the upper end of the conveyor will swing upwardly about the axis 36. The conveyor is driven by means of a sprocket chain 40 connected with the upper end of the conveyor and also connected with the shaft 36 from which communication is made by sprocket chain 41 to the driving shaft 17. This driving connection permits the adjustment of the conveyor just as the sprocket chain 23 permits the adjustment of the mixer 8.

The machine is driven by means of sprocket chains 42 connected with the large wheels 2 and also connected with a cross shaft 43 which is in turn connected by sprocket chain 44 with an idle shaft 45 driven by the driving shaft 17. A clutch 48 is provided for the driving mechanism for the cutting cylinder, the operation of this clutch permitting said driving mechanism to be thrown into and out of operation. A differential 49 is provided for the mechanism for driving the main driving wheels 2. A clutch 50 is provided for the mechanism for driving the traveling conveyor, by which said mechanism may be thrown into and out of operation to operate said conveyor. The handle 21 may be used either to elevate and lower the rotary cutting device or cylinder 8, or to elevate and lower the traveling conveyor. The one handle is used for both reels and the two reels are close enough together so that another handle could not be used, whereby one of said mechanisms is properly adjusted before the other is adjusted.

With reference to the vibratory support or hopper 51, the front end of this hopper is preferably lower than the rear end, so that the sand may slide forwardly and be dumped in any desired place. As an arrangement for vibrating or agitating the member 51, I show mechanism comprising a connecting rod 52 operated by an eccentric on the shaft 17 and connected with a bell crank 53 which is connected by a link 54 with the bracket 55 on the under side of the hopper 51. Thus the rotation of the shaft 17 operates to vibrate vertically the rear end of said member 51. When the conveyor is not in use, it is desired to lock the hopper against vibration, and to this end there is shown a pivoted lever 56 provided with a roller 57 which may be swung up against the under side of the hopper 51. A ratchet wheel 58 having a dog 59 will hold the lever 56 in any position to which it may be adjusted and thereby hold the hopper 51 upwardly against vibration. The link 54 is disconnected from the bracket 55, thereby disconnecting the trough from the vibrating mechanism to permit it to be held stationary.

Thus by using the rotary cutting member 8, the sand may be cut or piled or both; and by using the traveling conveyor or elevator 10, the sand may be riddled. Either one of these members may be used as desired. 70 Thus by one machine I am able to secure all these operations.

It will be understood that changes and modifications may be made without departing from the spirit of the invention. 75

What I claim is:

1. The combination with the machine frame, of a sand cutting device for cutting sand for foundry purposes mounted for vertical adjustment, flexible connectors for 80 raising and lowering the same, a reel for said flexible connectors, a traveling conveyor arranged in a substantially vertical manner and mounted for vertical adjustment relatively to the machine frame, a hopper located to receive material lifted by the conveyor, sprocket chains for driving the cutting device and traveling conveyor, means for vibrating the receiving hopper and a power generator for driving said 90 sprocket chains and agitating mechanism.

2. A sand cutting machine comprising a carriage movable over a floor, a frame pivotally connected thereto, a cutting device mounted at the free end of said frame, a flexible connector connected with said frame for elevating and lowering the cutting device, a reel for said connector, a traveling conveyor having a sliding connection with said carriage, driving mechanism whereby 100 either the sand cutting device or the traveling conveyor may be driven selectively, and a riddling device adapted to receive sand lifted by the conveyor.

3. A sand cutting machine adapted for 105 movement over a foundry floor having means for cutting sand on said floor for foundry purposes, and also having means for gathering said sand and lifting it from the floor, said sand cutting and sand gathering means 110 being mounted for adjustment so as to permit them to be moved into and out of substantially the same operative position, whereby either one or the other may be used in such operative position as desired. 115

4. A machine of the class specified having mechanism for cutting sand for foundry purposes, and also having mechanism for gathering and lifting sand, said sand cutting and sand gathering mechanisms being 120 mounted for adjustment to permit them to be moved into and out of substantially the same operative position, whereby one or the other may be used as desired.

5. A sand treating machine for use in 125 foundries, comprising a rotary member provided with cutting blades for cutting sand for foundry purposes, and also having a riddling mechanism and conveying means for conveying sand to said riddling mecha- 130

nism, and means for mounting said rotary cutting member and said conveying means so that either one or the other may be moved into an operative position to allow the use of one or the other as desired.

6. A sand cutting and treating machine comprising a chassis mounted on wheels for movement over a foundry floor, a cutting cylinder adjustably attached to said chassis, a traveling conveyor for gathering and raising sand adjustably attached to said chassis, and means for independently adjusting said cutting cylinder and said conveyor whereby they may be alternately placed in operative position for the treatment of material upon said floor.

7. A sand cutting and treating machine comprising a chassis mounted on wheels for movement over a foundry floor, a cutting cylinder adjustably attached to said chassis, a traveling conveyor for gathering and raising sand adjustably attached to said chassis, a screening mechanism adapted to receive sand from said conveyor, and means for independently adjusting said cutting cylinder and said conveyor whereby they may be alternately placed in operative position for the treatment of material upon said floor.

8. A sand treating mechanism comprising a chassis mounted upon wheels for movement over a foundry floor, a cutting cylinder having a plurality of blades, said cylinder being mounted for movement about its own axis and for vertical movement with respect to the chassis, a traveling conveyor for gathering and raising granular material, said conveyor being adjustably mounted on said chassis for vertical movement with respect

thereto, a screening mechanism positioned to receive material elevated by said conveyor, and means for independently and alternately adjusting said cutting cylinder and said conveyor into operative and inoperative positions whereby material upon said floor may be either operated upon by said cutting cylinder or may be elevated by said conveyor and deposited upon said screen.

9. A machine for treating fine material upon a foundry floor, comprising a chassis mounted for movement thereover, a cutting cylinder comprising a plurality of radially extending cutting blades, a member pivotally connected to said chassis, said cutting cylinder being rotatively mounted upon said member, means for causing pivotal movement of said member whereby said cutting cylinder may be adjusted into operative or inoperative position, a conveyor system comprising a plurality of traveling buckets, a support for said conveyor system and means for raising and lowering said support whereby the same may be brought into operative or inoperative position, a screen adapted to receive material from said conveyor, means for vibrating said screen whereby the screening operation is facilitated, the said aforementioned means for adjusting the cutting cylinder and for adjusting the conveyor being operable alternately whereby the material being acted upon may be either cut by said cylinder or may be elevated by said conveyor and screened.

In witness whereof, I hereunto subscribe my name this 3rd day of August, A. D., 1921.

ELMER A. RICH, JR.
